CLAIM

The ornamental design for a keyboard, as shown and described.

DESCRIPTION

1. Keyboard

1.1 : Bottom

1.2 : Bottom, front and right side perspective

Drawings 1.1 to 1.2 depict an ornamental design for a keyboard; the evenly dotted broken lines in drawings 1.1 to 1.2 illustrate unclaimed features of a keyboard and form no part of the claimed design.

1 Claim, 2 Drawing Sheets
